UNITED STATES PATENT OFFICE.

ONESIME ISAIE BERGERON, OF ST. GREGOIRE, CANADA, ASSIGNOR OF ONE-HALF TO L. EDMOND DUFRESNE, OF THREE RIVERS, CANADA.

CLOTHES-PIN.

SPECIFICATION forming part of Letters Patent No. 633,981, dated October 3, 1899.

Application filed January 9, 1899. Serial No. 701,586. (No model.)

To all whom it may concern:

Be it known that I, ONESIME ISAIE BERGERON, a subject of Her Majesty the Queen of Great Britain, residing at St. Gregoire, county of Nicolet, Province of Quebec, Canada, have invented certain new and useful Improvements in Clothes-Pins, (for which I have obtained Canadian Patent No. 61,594, dated November 3, 1898;) and I do hereby declare the following to be a full, clear, and exact description of the invention, such as will enable others skilled in the art to which it appertains to make and use the same.

My invention relates to improvements in clothes-pins, and has particular relation to that class of such devices which are adapted to be retained on the clothes-line.

The object of my invention is to provide a construction of this character which can be readily placed into and out of an operative position, which will securely hold the clothes in position without tearing, which is neat and attractive in appearance, durable in construction, and which can be made at a moderate cost.

To these and other ends my invention consists in the improved construction and combination of parts hereinafter fully described, and particularly pointed out in the appended claim.

In the drawing the figure represents a perspective view of a portion of a clothes-line having several pins in position, one being shown in inoperative position, the remainder being shown in operative position.

The pin is formed of two members A B, bent into the shapes shown in the drawing, and now to be described, each member being formed of a single piece of material, preferably resilient wire. The wire forming the member A is bent laterally, as at a, approximately at its center, the bent portion being carried slightly inwardly, as at a', forming the loop a². The wire is then bent at an angle, as at a³, extending in opposite directions, the outwardly-extending portions forming the bearings a⁴ for the member B. The wire is again bent laterally, as at a⁵, and extended downwardly a suitable distance, the ends being bent inwardly and joined, as at a⁶. The wire forming the member B is also bent lat-

erally, as at b, approximately at its center, the bent portion being carried downwardly and coiled, as at b', around the bearings a⁴ of the member A. The wire is carried forwardly from the coils, bent semicircularly, as at b², and carried backwardly a suitable distance, as at b³, then bent downwardly, as at b⁴, having its ends bent rearwardly, as at b⁵, and then laterally in opposite directions, as at b⁶.

As shown in the drawings, the clothes-line C is passed between the members, the clothes-pin when not in use being in the position shown in Fig. 1, the portion B² resting on the line C.

When it is desired to secure a cloth, such as D, in position, the pin is rotated to bring the looped ends downward and the cloth inserted between the respective loops. The pin is now drawn downward over the line, the thumb resting on the portions b³ while the index-finger rests against the portions a⁵. The drawing of the pin downward causes the portions a⁵ and b⁴ to pass on opposite sides of the line, thereby forcing the looped ends together. To release the cloth, the same positions are assumed by the thumb and index-finger, but the pin is pushed upwardly until the portion b² abuts against the line, when the pressure by the thumb against the portion b² will cause the looped ends to open and release the cloth.

It will be readily seen that as the pin is drawn downward over the line the pressure on the looped ends is gradually increased, the two members being pivotally connected.

The advantages of this construction are thought to have been clearly set forth.

While I have herein shown a preferred form of carrying my invention into effect, yet I do not desire to limit myself to such preferred details of construction, but claim the right to use any and all modifications thereof which will serve to carry into effect the objects to be attained by this invention in so far as such modifications and changes may fall within the spirit and scope of my said invention.

Having thus described my invention, what I claim as new is—

A clothes-pin, adapted to be movably secured on a clothes-line, said pin comprising

two members pivotally connected, each of said members having a looped end, one of said members having a laterally-extending loop adapted to support said pin on the clothes-line when in inoperative position, and each member having extending portions adapted to be wedged into operative position and held therein, by the passage of said mem-

bers over the clothes-line, substantially as described.

In witness whereof I have hereunto set my hand in the presence of two witnesses.

ONESIME ISAIE BERGERON.
